Arthur M. Nelson

UNITED STATES PATENT OFFICE

WALTER B. TEMPLETON, OF CHICAGO, ILLINOIS

BAND AND CONNECTION

Application filed April 21, 1930. Serial No. 445,857.

This invention relates to improvements in band end connections and it consists of the matters hereinafter described and more particularly pointed out in the appended claims.

The primary object of the invention is to provide a simple and efficient device to connect the ends of a tensioned band together, such as are used upon bales, bundles, boxes and barrels as the retaining member therefor.

Another object of the invention is to provide such a device that in no manner interferes with the operation of the tools now used to draw the band ends together.

Still a further object of the invention is to provide a device of this kind which comprises two pivotally connected arms having ends bent to engage with overlapped portions of a retaining band and thereafter indented thereinto to hold said band ends together against their normal separating action.

These objects of the invention as well as others together with the many advantages thereof will more fully appear as I proceed with my specification.

In the drawings:

Fig. 1 is a fragmentary perspective view of one corner of a box or other article, showing the manner of overlapping the ends of the retaining band before applying my improved connecting device thereto.

Fig. 2 is a view similar to Fig. 1 with my improved device in position to hold the overlapping band ends together.

Fig. 3 is a perspective view of my improved band end connecting device in its wide open position.

Fig. 4 is a top plan view of the device in position upon a pair of overlapping band ends to secure them together.

Fig. 5 is a view similar to Fig. 4 showing a modified form of the invention.

Figs. 6 and 7 respectively are detailed sectional views on an enlarged scale as taken on the lines 6—6 and 7—7 respectively of Fig. 4.

In general my improved device which is substantially X-shaped comprises a pair of flat lever like members pivoted together at a point midway between the ends thereof. A corner portion of each end is bent downwardly and then inwardly so as to embrace edge

portions of the overlapped band ends to be connected, which corner portions are operated upon by a suitable tool that indents or deforms them and the engaged edge portions of the band to not only lock the device to the band ends but also lock the band ends to each other.

Referring now in detail to that embodiment of the invention best illustrated in Figs. 1 to 4 inclusive of the drawings, 1 indicates as a whole a thin metallic band such as is now extensively used for retaining boxes, bales, barrels and bundles against opening up in shipment. Such a band is usually of a length greater than the circumference of the article 2 to be bound so that the ends 3 and 4 respectively of the band may be brought into overlapping relation.

Associated with such a band, is a device embodying my invention and which is indicated as a whole as at 6. Said device comprises a pair of lever like members 7—7 of flat strip metal pivoted together at a point midway between their ends in any suitable manner. Preferably a part of one member is upset into a part of the other to provide a rivet like pivotal connection between said members as best shown at 8 in Fig. 7.

One corner at each end of each member is bent downwardly as at 9 and then inwardly to form a tongue 10 which when the device is in place upon associated band ends, engages under the lateral edges of the same. Preferably to prevent the said members from folding too far into superposed relation with each other, I form in the body of each member a shoulder 11 in the manner of an indentation to engage the edge of the other member. This limits the relative folding of said member so that the device may be more readily handled and manipulated when applying the device to the overlapped ends of an associated band.

In the use of the device thus far described, a band 1 of the desired length is applied to the article 2 in the usual manner to surround the same and the band ends 3 and 4 are brought into overlapping relation. With a suitable tool, the band ends are drawn taut in opposite directions thus somewhat compressing the article in the plane of the band

so that the band may be aptly said to be tensioned.

While the band ends are thus held together one of the devices is laid upon said band ends after swinging the members 7 about the pivot 8 so that the tongues 10 pass or clear the edges of the overlapped band end. The said members are then swung in the other direction so that the bent over portions 9 approach each other and so that the tongues 10 associated therewith pass under said band edges. This brings the bent over portions 9 of said members into engagement with the edges of said band ends.

15 A suitable tool for the purpose is then applied to the opposed bent over ends 9 of the levers so as to deform or indent portions of said ends and adjacent band edges inwardly of the band so as to form notches 12 therein. 20 By means of said indentations or deformations, the device is securely attached to the band ends which in turn are attached to each other so that the overlapped ends of the band are securely held against separation under 25 the natural expanding tendency thereof when the operating tools mentioned have been removed therefrom.

30 In Fig. 5 I have illustrated a modified form of the device which comprises two members 7^a—7^a pivoted together at 8^a. In this instance said members do not cross each other as in the structure before described but each member has lateral arms 7^b—7^b, the ends of which are bent over as at 9^a and then under as at 10^a to there provide tongues as before. After 35 positioning such a device upon overlapped associated band ends, a suitable tool is employed to deform or indent the bent over portions 9^a of the device together with associated edge portions of the overlapped band ends so as to provide locking notches 12^a therein as before.

40 The device described is simple in construction and can therefore be made in large quantities at an extremely low cost. It may be easily applied and it securely holds the band ends against relative displacement.

45 While in describing the invention, I have referred in detail to the form, arrangement and construction of the several parts thereof, the same is to be considered merely as illustrative so that I do not wish to be limited thereto except as may be specifically set forth in the appended claims.

50 I claim as my invention:—

55 1. A device of the kind described comprising a pair of pivotally connected members having portions of each end thereof engaged against edge portions of overlapped band ends and which end portions of said pivotally connected members are intended to be indented into said edge portions of said band ends.

60 2. A device of the kind described comprising a pair of pivotally connected members

having portions of each end thereof bent downwardly to engage against edge portions of associated overlapped band ends with parts thereof bent to engage under said band ends, said first mentioned end portions of said members being intended for indentation into and together with said edge portions of said band ends.

65 3. A device of the kind described each comprising a pair of flat strip members pivotally connected at a point between their ends and having a part of each end thereof bent downwardly to form portions adapted for engagement with the edges of a pair of overlapped band ends, which portions are intended to be indented into said edges of said band ends.

70 4. A device of the kind described each comprising a pair of flat strip members pivotally connected at a point between their ends and having a part of each end thereof bent downwardly and inwardly under and spaced from said members.

75 5. A device of the kind described each comprising a pair of flat strip members pivotally connected at a point between their ends and having a part of each end thereof bent downwardly and inwardly under and spaced from said members, one of which is formed to provide a stop to be engaged by the edge of the other member to prevent folding together of said members in substantially a superposed relation.

80 6. As an article of manufacture, a strip 85 of sheet metal adapted for connection to and use with another similar strip, said strip being formed at diagonally opposite corners with bent down portions that terminate in bent under extremities spaced from and arranged within the planes of the edges of the 90 body of the strip itself.

95 In testimony whereof, I have hereunto set my hand, this 17th day of April, 1930.

100 WALTER B. TEMPLETON.
